SHEET DEFLECTOR

Application filed November 23, 1928. Serial No. 321,321.

This invention relates to improvements in sheet deflectors, and has reference particularly to movable deflectors adapted to be actuated by the travel of the sheets themselves to direct successive sheets into different courses. The invention has utility in connection with paper handling machines in which large sheets are cut apart and the sections thereof fed through the machine in single file, the deflector of the present invention serving to direct like sections into the same courses for separate stacking.

One of the objects of the invention is the provision of simple and effective means for shifting a movable deflector, such means to be controlled by the movement of the sheets themselves without regard to their spacing or the time interval between successive sheets.

Another object is the provision of a mechanism of the character described in which force is built up to cause the travel of the front edge of the deflector across the path of the paper immediately after the rear edge of the paper is released from the feeding means just behind it, the paper sheet itself holding the deflector back from the completion of its shifting movement until the rear edge of the sheet is free to swing with the deflector. In this way the swinging of the deflector is effected before the rear edge of the sheet has passed the front edge of the deflector, and the latter is set for the next sheet no matter how close the spacing of the successive sheets may be.

Another object of the invention is the provision of means actuated by the swinging of a shoe in one of the courses for shifting the deflector without in any way affecting the setting of the shoe in the other course, the shoe being returned to normal position by spring pressure after the travel of the sheets thereover.

Other objects and features of novelty will appear as we proceed with the description of that embodiment of the invention which, for the purposes of the present application, we have illustrated in the accompanying drawings, in which—

Fig. 1 is a plan view of a portion of a sheet

stacker embodying the invention, a fragment of the delivery end of a folding or other paper handling machine in operative relation with the stacker being also illustrated in section upon the line 1—1 of Fig. 2;

Fig. 2 is a side elevational view of the same;

Fig. 3 is a vertical sectional view taken substantially on the line 3—3 of Fig. 2;

Fig. 4 is a vertical sectional view at right angles to Fig. 3 and taken substantially on the line 4—4 of Fig. 3, this view showing the deflector mechanism set to direct a sheet onto the upper stacker belt; and

Fig. 5 is a view similar to Fig. 4, showing the deflector mechanism in position to direct a sheet onto the lower stacker belt.

Similar reference characters refer to like parts throughout the views.

In the drawings, the front and rear members of a stacker machine frame are indicated at 10 and 11, respectively. Between these members 10 and 11 there are mounted two superposed endless stacker belts 12 and 13, the upper belt 12 being supported at one end and driven by a roller 14 and the lower belt 13 being similarly supported and driven by a roller 15. The machine is designed to deliver and collect signatures of one kind on belt 12 and those of another kind on belt 13.

The stacker of the present invention is intended to be positioned at the delivery end of a folding machine or other paper handling machine, and in the attached drawings we have illustrated a fragment of such a machine with its front and rear frame members 16 and 17 and delivery feed rollers 18 and 19, on the front ends of which are mounted intermeshing gears 18' and 19', respectively. The drive for the stacker mechanism is to be taken from the paper handling machine, and for that purpose, in the present instance, we have pinned a gear 20 to the roller 19 inside the frame member 16, and have mounted an idler 21 upon the stacker frame member 10 in position to mesh with the gear 20.

The idler 21 transmits power to a pair of intermeshing gears 22 and 23 which are carried upon the forward ends of two feed rolls 24 and 25, respectively. These rolls

receive into the stacker mechanism the sheets delivered single file by the delivery rolls 18, 19 of the paper handling machine.

Directly in the rear of the feed rolls 24 and 25, speaking with reference to the travel of paper sheets through the machine, is a movable deflector 26 which is provided at its ends with trunnions 27 that have bearing in the frame members 10 and 11. The axis of these trunnions is in, or close to, the path of the paper sheets leaving the feed rolls 24, 25, and the front edge 28 of the deflector is adapted to swing across that path from one side to the other thereof. The movement 10 of the deflector into the position illustrated in Fig. 4 causes the next sheet to take the upper course indicated in that figure at A, and the movement of the deflector into the position illustrated in Fig. 5 causes the next sheet 15 to take the course indicated in the latter figure by the reference character B.

Sheets following the course indicated at A pass between a solid metal feed roll 29 and a feed roll 30 furnished with spaced friction discs. Those taking the course indicated at B travel between a solid metal roll 31 and a roll 32 similar to the roll 30.

Near the top of the frame member 10 we provide a pivot pin 33 on which is mounted an adjustable bracket 34. This bracket has an extension arm 35 in which is fixed a threaded rod 36 that is movable through a smooth opening in a post 37 which projects inwardly from the frame member 10. A coil spring 38 surrounds the rod 36 between the extension arm 35 and the post 37, and a second coil spring 39 surrounds the rod 36 beneath the post 37, this latter spring being compressed more or less by an adjusting nut 40. The latter nut is preferably held in adjusted position by a lock nut 41.

The bracket 34 is provided with a bearing in which is rotatably mounted a shaft 42, which extends beyond both ends of the bearing. On its rear end the shaft 42 has pinned thereto a shoe 43 which, in its normal position indicated in Figs. 1 to 4 inclusive, extends between rolls 29 and 30, lying within the space between two friction discs on the roll 30. This shoe is carefully finished on its outer surface to an arc concentric with the axis of the shaft 42, and is adjusted by means of the nut 40 so as to lie close to the surface of roll 29, in order that the thickness of the sheets or folded signatures which travel between these rolls may be sufficient to cause the swinging of the shoe. On the forward end of the shaft 42 there is pinned a hub 44. This hub carries two projecting arms 45 and 46. The arm 45 has attached thereto a tension spring 47, the opposite end of which is secured to a pin 48 fixedly mounted in the post 37 or other rigid part of the machine. The spring 47 thus tends to hold

the shoe 43 in its normal position illustrated in Figs. 1 to 4, inclusive.

The arm 46 has an opening therethrough in which is loosely mounted a rod 49 threaded at its upper extremity. An adjustable head for the rod 49 is provided by means of a pair of nuts 50. At its opposite end the rod 49 is formed with an integral plate 51 which is slotted to receive a pin 52 that is threaded into a socket in the front end of deflector 26. Between the plate 51 and the arm 46 the rod 49 is surrounded by a coil spring 53. Hence, the oscillation of the shaft 42 in an anticlockwise direction, as viewed in Fig. 2, tends to depress the pin 52 and to swing the deflector 26 on its trunnions 27 out of the position illustrated in that figure and in Fig. 4 toward the position illustrated in Fig. 5.

A shoe 54, similar to the shoe 43, is similarly mounted upon a shaft 55 which is rotatably supported in a bracket 56 that is mounted upon a pivot 57 and provided with an extension arm 58 carrying a rod 59 that runs freely through a perforated lug 60 on the frame member 10, coil springs 61 and 62 surrounding the rod 59 on opposite sides of the lug 60, and nuts 63 and 64 threaded onto the free end of the rod 59 serving to regulate the compression of spring 62 and the consequent adjustment of the bracket 56. The springs 61 and 62 assist in the adjustment of the shoe 54. By adjusting the nut 63 the tension of spring 62 may be increased or decreased, which in turn will increase or decrease the tension of spring 61. By increasing the tension of spring 62 the rod 59 is moved toward the left against the pressure of spring 61, thereby drawing the extension arm 58 toward the left and swinging the bracket 56 clockwise about its center 57 to a small extent. This decreases the clearance between shoe 54 and its cooperating roller 31. Movement of the nut 63 in the opposite direction enables spring 61 to move the shoe 54 away from the roller 31. Furthermore, spring 62 provides a resilient mounting for the bracket 56, so that if any unduly thick signature attempts to pass between the shoe 54 and roller 31 the spring will be compressed and will allow the shoe 54 to move away from the roller sufficiently to permit the unusual thickness of paper to pass on through the machine, thereby avoiding damage due to stopping the mechanism while the power is on. It will be understood of course that the springs 38 and 39 have functions identically

the same as those of springs 61 and 62. The outer end of the shaft 55 carries one arm 65 similar to the arm 46, but having attached thereto a coil spring 66 which corresponds in function with the coil spring 47 and is attached to a pin 67 threaded into the frame member 10 of the machine. The arm 65 is connected with the pin 52 by a rod 68 having an adjustable head formed by nuts 69.

and having an inner end in the form of a slotted plate 69, with a surrounding coil spring 70, all of which parts correspond exactly in construction and operation with the parts 49, 50, 51 and 53, previously described.

On the forward side of frame member 10 there is an idler 9 meshing with gear 22 and with a gear 71 on the forward end of roll 32. The latter gear is one of a train of four gears 10 71, 72, 73 and 74 on the rolls 32, 31, 29 and 30, respectively, by means of which those rolls are driven.

The drive for the stacker belt 12 is taken off the gear 72 which meshes with a larger gear 15 75 on the forward extremity of roller 14. The drive for the stacker belt 13 is taken off gear 71 which meshes with an idler 76 supported upon a stub shaft 77 mounted in the frame member 10, the idler 76 in turn meshing with a larger gear 78 on the forward extremity of roller 15. The belts 12 and 13, therefore, move at a relatively slow rate of speed, and obviously the design of the machine can be varied in this respect to 25 provide any speed of travel of the belts 12 and 13 which may be desired.

In Fig. 5 we have shown at A' the position of a sheet next in advance of that indicated at B, this view being intended to illustrate the condition where the forward edge of one sheet is directly behind or practically touching the rear edge of the preceding sheet, the shoe 43 being still unreleased by the sheet A' while the forward edge of the sheet B is 35 just about to swing the shoe 54 upon its axis.

Operation.—Assuming that the various parts of the mechanism are in the positions illustrated in Fig. 4, with a sheet A traveling over the upper surface of the deflector 26, this sheet will be guided upwardly by the 40 inclined surface of the deflector so that its forward edge is directed into the angle between the roll 29 and the shoe 43. The rolls 29, 30 now grip the sheet and feed it along, and in this operation the shoe 43 is swung upon its axis into the position illustrated in 45 Fig. 5, where it is held by the traveling sheet or signature against the tension of spring 47 until it is cleared by the passage of the rear edge of the sheet. The swinging of the shoe 43 from its normal position into the position of Fig. 5 causes the arm 46 to press upon the upper end of coil spring 53. Thereupon the plate 51 at the lower end of rod 49 is 50 pressed downwardly against the pin 52 by the spring 53 tending to swing the deflector 26 upon its trunnions 27. The sheet A, however, which is still within the grip of rolls 24, 25 prevents the rear edge 28 of the deflector from swinging across the path of the sheet. Consequently, the swinging of shoe 43 acts first to move deflector 26 sufficiently to bring the front edge 28 thereof against the paper sheet A, and thereafter to build 55 up pressure in the compression spring 53.

Now, as soon as the sheet A has progressed far enough so that its rear edge is released by the rolls 24, 25, this built up pressure acts instantaneously to continue the movement of the deflector, swinging the front edge 28 thereof across the natural path of the paper into the position illustrated in Fig. 5. This swinging of the deflector is permitted by the slot in plate 69 on the rod 66; that is to say, the pin 52 in thus moving downwardly does not transmit motion to the rod 66 but merely moves from the top of the slot in plate 69 to the bottom of that slot.

The next sheet or signature B strikes against the lower side of deflector 26, as indicated in Fig. 5; and is deflected downwardly to an extent sufficient to direct it between rolls 31 and 32. The previous sheet in the meantime travels forward onto stacker belt 12, maintaining the shoe 43 in its outer position illustrated in Fig. 5 until the rear edge of that sheet has passed beneath the tip of the shoe, as indicated in that figure, whereupon the spring 47 acts to turn the shaft 42 and swing the shoe 43 back to its normal position between the rolls. The sheet B now acts to swing the shoe 54 and the deflector 26 operatively connected therewith, until the front edge 28 of the latter bears against the upper surface of the sheet and builds up pressure in spring 70, which pressure becomes effective, as soon as the rear edge of the sheet passes out of the control of rolls 24 and 25, to swing the deflector back to its first position illustrated in Fig. 4. After the rear edge of sheet B has passed beyond the tip of shoe 54, the latter is released and the spring 66 brings it back into normal position. Sheet B in the meantime has been deposited upon stacker belt 13. The cycle of operations then repeats itself.

Although in the present disclosure we have illustrated and described with considerable particularity one preferred embodiment of the invention, we desire it to be understood that such detailed disclosure is primarily for purposes of illustration and is not to be construed as a limitation upon the scope of the invention.

Having thus described our invention, what we claim is:

1. In a paper handling machine, means for causing the sheets to travel single file in a given path, a deflector for directing sheets from said path into either of two different courses, a shoe in each of said courses adapted to be shifted by the travel of a sheet therethrough, means associated with each shoe for shifting the deflector when the shoe is shifted, and independent means associated with each of said shoes for returning it to normal position when not in engagement with a sheet traveling through that course.

2. In a paper handling machine, means for causing the sheets to travel single file in a

given path, a deflector for directing sheets from said path into either of two different courses, a shoe in each of said courses adapted to be shifted by the travel of a sheet there-
5 through, means associated with each shoe for shifting the deflector when the shoe is shifted, and means associated with each shoe for re-
turning the shoe to normal position when not in engagement with a sheet traveling through
10 that course, said two last named means being independent of each other and independent of the said deflector shifting means.

3. In a paper handling machine, means for causing the sheets to travel single file in a given path, a deflector for directing sheets from said path into either of two different courses, a shoe in each of said courses adapted to be shifted by the travel of a sheet there-
15 through, means associated with each shoe for shifting the deflector when the shoe is shifted, and a separate resilient means associated with each shoe for returning it to normal position when not in engagement with a sheet traveling through that course.

25 4. In a paper handling machine, means for causing the sheets to travel single file in a given path, a deflector for directing sheets from said path into either of two different courses, a shoe in each of said courses adapted to be shifted by the travel of a sheet there-
30 through, means associated with each shoe for shifting the deflector when the shoe is shifted, each of said means being capable of moving the deflector in one direction only,
35 and means associated with each of said shoes for returning it to normal position when not in engagement with a sheet traveling through that course.

5. In a paper handling machine, means for causing the paper sheets to travel single file in a given path, a deflector for directing sheets from said path into either of two different courses, a shoe in each of said courses adapted to be shifted by the travel of a sheet therethrough, and means operatively associated with each shoe and with the deflector for building up pressure tending to shift the deflector, whereby the deflector is shifted as soon as the rear end of the sheet traveling over its surface is free to move with the deflector.

6. In a paper handling machine, feeding means adapted to provide single file travel of sheets, means for directing sheets received from said feeding means into either of two different courses, said means comprising a pivoted shoe adapted to be swung in a given direction by the travel of a sheet, a movable deflector, and an operative connection, between said shoe and deflector adapted to build up pressure tending to shift the deflector, whereby the deflector is shifted as soon as the rear edge of the sheet traveling over its surface is free to move with the deflector.

7. In a paper handling machine, feeding means adapted to provide single file travel of sheets in a given path, means for directing sheets from said path into either of two different courses, said means comprising a pivoted shoe adapted to be swung in a given direction by the travel of a sheet, a pivoted deflector one edge of which is adapted to move transversely across said path, and an operative connection between said shoe and deflector adapted when said shoe is shifted to move the said edge of the deflector against the said sheet and to build up pressure tending to swing the deflector across air path as soon as the travel of the sheet permits.

8. In a paper handling machine, means for causing the paper sheets to travel single file in a given path, a deflector for directing sheets from said path in either of two different courses, a shoe in each of said courses resiliently urged toward normal position and adapted to be shifted therefrom by the travel of a sheet through that course, and means operatively connecting each of said shoes with said deflector tending to shift the latter when either of said shoes is shifted, said last named means including one-way connections, whereby the movements of the shoes are entirely independent of each other.

In testimony whereof, we hereunto affix our signatures.
